UNITED STATES PATENT OFFICE.

RENE CONINGS, OF PITTSBURG, KANSAS.

FUSE-IGNITER.

970,889.

Specification of Letters Patent. Patented Sept. 20, 1910.

Application filed November 2, 1909. Serial No. 525,866.

To all whom it may concern:

Be it known that I, RENE CONINGS, a subject of the King of Belgium, and a resident of Pittsburg, in the county of Crawford and State of Kansas, have invented a new and Improved Fuse-Igniter, of which the following is a full, clear, and exact description.

This invention relates to fuse igniters for use in mines and the like, to ignite the fuses used to detonate blasting or other explosive charges, and relates more particularly to a fuse igniter having an igniting chamber, means for introducing the end of a fuse into the chamber, and means for igniting the fuse within the chamber so that no flame or spark can escape from the device.

The object of the invention is to provide a simple, inexpensive and efficient fuse igniter, which can be easily and expeditiously manipulated, by means of which fuses can be ignited in mines or the like, without danger of causing explosions due to the firing of accumulations of gas which may have collected in the neighborhood of a fuse, and which involves no loss of time or labor in the lighting of the fuse.

The invention consists in the construction and combination of parts to be more fully described hereinafter and particularly set forth in the claims.

Reference is to be had to the accompanying drawings forming a part of this specification, in which similar characters of reference indicate corresponding parts in all the views, and in which—

Figure 1 is a partial, longitudinal section of an embodiment of my invention, showing a fuse associated therewith; Fig. 2 is a side elevation of the device; Fig. 3 is an enlarged end view showing the means for holding the fuse; Fig. 4 is an enlarged, transverse section on the line 4—4 of Fig. 2; and Fig. 5 is a similar view on the line 5—5 of Fig. 2.

Before proceeding to a more detailed explanation of my invention, it should be clearly understood that while the device is particularly useful for igniting the fuses of blasting charges in mines and the like, it can also be advantageously employed for igniting fuses or similar articles under other conditions, and that it obviates the necessity of using matches or uncovered flames for the purpose. In certain classes of mines, particularly in coal mines, gases which are

dangerously explosive often accumulate in various parts of the workings, and unless certain precautions are taken these accumulations of gas can easily be ignited to result in dangerous explosions. To obviate the possibility of such explosions, lamps known as Davy's lamps are used, in which the flames are incased in wire gauze or other reticulate or perforate hoods or covers, which in accordance with a well-known scientific principle prevent the transmission of the flame to the outside of the gauze. I have employed this principle in my fuse igniter, which includes a chamber wherein the end of the fuse is received and ignited by suitable means, the chamber having a reticulate or perforate wall to permit the entrance of the necessary air, though preventing the escape of flame or sparks to the outside.

Referring more particularly to the drawings, I employ a wick container 10 fashioned from sheet metal or the like and preferably of substantially cylindrical form, and provided with rounded extremities 11 and 12. The extremity 11 may be provided with an eye 13 by means of which the igniter can be hung upon a hook or can be attached to a carrying loop or the like. The container has a closing slide 14 arranged to move in guides 15, and provided with a projection 16 by means of which it can be manipulated. The slide serves to close the opening of the container, and permits the introduction into the same of the wick 17. The end 12 of the container has associated therewith the wick tube 18 through which the wick 17 extends. The wick tube intermediate its ends is extended to form a substantially cylindrical barrel 19 in which are journaled grooved rollers 20 adapted to grip the wick and arranged to be manipulated from the outside of the barrel by means of a stem 21 having a burred head 22. By turning the head 22 in one direction or the other, the wick is advanced longitudinally of the wick tube by means of the rollers which are suitably geared together in the usual manner. The rollers are operated by suitably incased gears (not shown).

The igniting chamber 23 is preferably cylindrical in form and has openings 24 at opposite sides. These openings are covered with metal gauze 25 or the like, which may be of any suitable reticulate or perforate form. The igniting chamber has a neck 26 adapted

to be slidably mounted at the end of the wick tube 12, and having a bayonet slot 27 adapted to co-act with a stud 28 of the wick tube to hold the igniting chamber removably in position. It will be understood that by means of the advancing device the wick 17 can be moved into or retracted from the igniting chamber as desired. The wick is preferably of cotton, and when ignited merely smolders and is consumed slowly and gradually. The end of the igniting chamber remote from the container is open and has mounted thereon a fixed jaw 29 having a substantially cylindrical, longitudinal groove 30 and at the ends laterally extended lips 31. The igniting chamber has extensions 32 between which is pivoted, by means of a suitable pin 33, a movable jaw 34 having a longitudinal, substantially semi-circular groove 35 adapted to register with the groove 30 to form a substantially circular opening in which part of the fuse 36 can be received. The jaw 34 has a handle 37 by means of which it can be conveniently manipulated, the handle extending longitudinally of the device as is shown most clearly in Fig. 2. A spring 38 tends to hold the movable jaw normally closed. The movable jaw, it will be seen, seats against the fixed jaw between the lips 31 and the igniting chamber, so that when the end of a fuse is held between the jaws, air is excluded from entering the igniting chamber through the open end thereof.

The container of the igniter serves as the means for grasping it, the device being so proportioned that it can be conveniently held in any way with the thumb upon the handle 37. When it is desired to ignite a fuse the handle 37 is depressed to open the jaws, and the end of the fuse which has previously been split by means of a knife or other suitable tool, is inserted into the igniting tube. The wick, which has been previously lighted, so that it is smoldering, is then turned up until it is brought into engagement with the end of the fuse so that the latter is ignited. The handle 37 is again depressed to release the fuse and the device is withdrawn. The operator then passes to a place of safety. It will be understood that these operations can be performed in a very short space of time and that there is no danger of communicating the fire or sparks to any gas which may have accumulated in the neighborhood of the fuse, for the spark travels along within the fuse after the latter has been lighted at the split end.

Having thus described my invention, I claim as new and desire to secure by Letters Patent:

1. A device of the class described, comprising an igniting chamber, means for removably holding the end of a fuse within said chamber, a wick for igniting the fuse,

and means for advancing said wick into said chamber.

2. A device of the class described, comprising a wick container, an igniting chamber associated therewith, and means for advancing a wick from said container into said igniting chamber, said igniting chamber having an opening adapted to permit the entrance of a fuse into said igniting chamber, and means for holding the fuse and closing said opening of said igniting chamber.

3. A device of the class described, comprising an igniting chamber having a perforate wall, means for removably holding the end of a fuse within said chamber, a wick for igniting the fuse, and means for advancing the wick into said chamber.

4. A device of the class described, comprising a wick-container, an igniting chamber associated therewith and having a wall fashioned from gauze, means for advancing a wick from said container into said igniting chamber, said igniting chamber having an opening adapted to permit the entrance of a fuse into said igniting chamber, and means for holding the fuse and closing said opening of said igniting chamber.

5. A device of the class described, comprising a wick-container having a wick tube, means for advancing a wick through said wick tube from said container, an igniting chamber associated with said wick tube adapted to receive the end of the fuse, said igniting chamber having a reticulate wall and at the end an opening, a fixed jaw at said opening, a movable jaw at said opening, said jaws being formed to receive the end of a fuse therebetween and being adapted to close said opening of said igniting chamber, and means for manipulating said movable jaw.

6. A device of the class described, comprising a wick-container having a wick tube, means for advancing a wick through said wick tube from said container, an igniting chamber associated with said wick tube and adapted to receive the end of the wick, said igniting chamber having a reticulate wall and at the end an opening, a fixed jaw at said opening, a movable jaw at said opening, said jaws being formed to receive the end of a fuse therebetween and being adapted to close said opening of said igniting chamber, said movable jaw having a handle associated therewith, and a spring controlling said handle, whereby said jaws are normally closed.

In testimony whereof I have signed my name to this specification in the presence of two subscribing witnesses.

RENE CONINGS.
